UNITED STATES PATENT OFFICE

EUGENE J. NEY, OF NEW YORK, N. Y.

WINDOW VENTILATOR

Application filed March 3, 1931. Serial No. 519,719.

The present invention relates to improvements in window ventilators, and has reference to the type disclosed in Letters Patent No. 1,734,641, granted to me on November 5, 1929.

The construction described in the said Letters Patent includes a deflecting frame, comprising an upper rail and a lower rail which are connected by side rails, and a screen frame which is hinged to the upper rail of said deflecting frame. While a construction of this type particularly adapts itself to wooden structures, difficulties are presented when metal bars are used in constructing the deflecting frame and these difficulties cannot be overcome when it is desired to mount a single heavy glass pane in the said deflecting frame.

The main object of the present invention is to construct a deflecting frame which overcomes the difficulties above referred to, and to generally simplify the structure.

With these and other objects in view, which will more fully appear as the nature of the invention is better understood, the same consists in the combination, arrangement and construction of parts hereinafter described, pointed out in the appended claims and illustrated in the accompanying drawing, it being understood that many changes may be made in the size and proportion of the several parts and details of construction within the scope of the appended claims, without departing from the spirit or sacrificing any of the advantages of the invention.

One of the many possible embodiments of the invention is illustrated in the accompanying drawing, in which:

Figure 1 is a perspective view showing the improved ventilator positioned on a window; Fig. 2 is a vertical section taken through the said ventilator, on a larger scale; and Fig. 3 is a section taken on line 3-3 of Fig. 2, on a still larger scale.

In the drawing, the numeral 10 indicates the lower sash of a window, slideable in a window casing 11. The ventilator, which is to be secured to the said casing, consists of two substantially triangular, preferably, sheet metal plates or brackets 12, attached by screws 13, or the like, to the vertical members

of the window casing immediately above the sill portion 14 thereof. These brackets are so attached to the casing that they permit of free sliding movement of the window sashes, their vertical edges 15 being for this purpose spaced from the lower sash. The plates project into the room, that is to say outward of the window frame, and their slanting edge portions 16 are each provided with two spaced flanges 17, forming a channel. Into these channels, which are in alignment, may be slid a deflecting frame 18, preferably made of metal. This frame extends across the entire width of the window opening and is adapted to receive a glass pane 19.

The deflecting frame is of U-shaped construction, it comprising a horizontal rail 20 from each end of which rises a vertical rail 21. Between these rails is mounted, preferably, detachably, the glass pane 19. On the upper free longitudinal edge of the glass pane is mounted a rubber or metal strip 22, for a purpose hereinafter to be described. In order to prevent rattling of the glass pane in the deflecting frame, springs 23 may be inserted into the vertical rails 21 of the frame, to bear against the said glass pane.

To the free ends of the vertical rails 21 is attached by hinges 25 a screen frame 26, which extends, in its operative position, horizontally from the inclined edge portions of the brackets 12 to the lower window sash, it being adapted to rest upon inwardly bent horizontal flanges 27 upon the brackets 12. The screen frame is made preferably of metal and covered with a fine meshed wire fabric 28, or the like, the said fabric being held upon the frame in any suitable manner, for instance by strips 29 which are sunk into grooves 30 in the screen frame. That rail 90 of the screen frame which is disposed adjacent the window sash carries a resilient strip 31 of felt, rubber or the like, the said strip being adapted to bear against the lower rail of the window sash or against the window pane when the sash is raised to permit ventilation of the room. To the screen frame is fixed a handle or knob 32, by means of which it may be raised or lowered, as required. To the lower rail of the deflecting

frame 18 is secured a resilient strip 33, of felt, rubber or the like, for contact with the sill of the window casing. The strips 31 and 33 serve, obviously, to make air-tight closures.

5 The operation of this device is as follows: When the device is in position on the window casing, as shown in the drawing, the lower window sash is raised until its lower rail is in abutment with the strip 31 on the screen 10 frame. Air entering through the fabric 28 passes into the room through the window aperture and is directed upwardly, thus avoiding direct draft. The fabric screens the air, permitting thorough ventilation, 15 without the accompanying annoyance of dust, dirt and insects. If necessary, the screen frame may be shifted around its hinges 25 onto the deflecting frame. More air will thus enter the room but dust, dirt 20 and insects will not be excluded therefrom. The rubber or metal strip 22 above described serves not only to make an air-tight joint with the screen frame but also to protect the window pane.

25 Both the deflecting frame and the screen frame may be composed of rails of any suitable cross-section, and they may be made of any suitable material, for instance extruded aluminum rails may be used in the construction 30 of these frames, and they may be hollow to decrease the weight thereof or to receive enlarged portions of the packing strips 31 and 33, as clearly shown in Fig. 2 of the drawing. By constructing the deflecting 35 frame of three rails only, the window pane may be detached therefrom when it is to be cleaned or replaced.

The rubber or metal strip 22 may be held in place on the deflecting frame by springs 40 34 (Fig. 3), which may be of any suitable construction and mounted on the vertical rails 21 of the deflecting frame. In the construction illustrated in Fig. 3 blade springs are employed, each spring being provided at 45 one of its ends with a loop 35, which is disposed within a rail 21. Through these loops pass screw bolts 36, which serve at the same time to secure the hinges 25 to the said rails. The free ends 37 of these springs bear against 50 the strip 22.

What I claim is:—

1. In combination with a window casing and a vertically sliding sash therein, of a pair of brackets secured to the vertical members of said casing immediately above the sill portion thereof so as to project into the room, a pair of channels formed in said brackets in alignment with one another, a deflecting frame slidable in said channels 55 and resting upon said sill, said frame comprising two rails adapted to be disposed in said channels and connected by a rail adapted to rest upon the window sill, a window pane slidably arranged in said deflecting frame, 60 horizontal flanges formed upon said brackets 65

in alignment with the free ends of those deflecting frame rails which are disposed in said channels, a screen frame hingedly secured to those rails of said deflecting frame which are disposed in said bracket channels 70 and adapted to rest upon the flanges of said brackets, the free longitudinal edge of said screen frame abutting against the lower rail of said sash when the latter is raised to permit access of air into the room through said 75 screen frame.

2. The combination according to claim 1, comprising a strip disposed upon the free edge of said pane, the rails of said deflecting frame being hollow, and a spring partly disposed in each rail located in said channels and secured to said rail, said springs bearing 80 against said strip.

Signed at New York city, in the county of New York and State of New York, this 17th day of February, A. D. 1931.

EUGENE J. NEY.
